UNITED STATES PATENT OFFICE.

JOHN CUTHBERT TRAILL, OF MALVERN, VICTORIA, AUSTRALIA.

SAFETY-PIN.

No. 823,905.

Specification of Letters Patent.

Patented June 19, 1906.

Application filed June 26, 1905. Serial No. 267,065.

To all whom it may concern.

Be it known that I, JOHN CUTHBERT TRAILL, a subject of the King of Great Britain and Ireland, residing at Malvern, in the 5 county of Bourke, State of Victoria, Commonwealth of Australia, have invented certain new and useful Improvements in Safety-Pins, of which the following is a specification.

The object of my invention is to provide an 10 improved form of safety-pin which may be used upon wearing-apparel or fastening ladies' boas and the like, but which is particularly applicable for use in fastening and hanging curtains, drapings, and the like, 15 which latter are usually suspended from elevated positions. In the past the safety-pins used for this purpose have by the weight of the curtain become distorted and the pin dragged from its holder or socket. This has 20 given the draping an unsightly appearance. In addition to this pins previously used for the purpose named were difficult of attachment and when attached did not form a regular plait. With my invention a pin is produced which overcomes these defects, is 25 cheap in first cost, is simple and effective in operation, and its construction is such that the heavier the curtain suspended by the pin the more securely the free ends of the pin re- 30 main within their socket. In addition to this a plait may be formed of any width, and the folds forming the plait may be coupled wherever desired. A curtain suspended by my improved pins has a more graceful ap- 35 pearance, inasmuch as the weight of the curtain drags the outer or spring ends of the pin downwardly, and the said outer ends as they droop a little carry portions of the plait with them, which gives the draping the de- 40 sired effect; but in order that my invention may be better understood I will now refer to the accompanying sheet of drawings, which are to be taken as part of this specification and read herewith.

45 Figure 1 is a blank of flexible wire from which my pin is formed. The ends are, as seen, sharpened. Fig. 2 is the same blank with the bay or pocket formed therein. Fig. 3 shows the pin partially formed. Fig. 4 is a 50 view of the manufactured pin. Fig. 5 is the back view of portion of a curtain, showing two of my pins in use. The suspending- hooks can be clearly seen. Fig. 6 is a front view of a pin with a modification. Fig. 7 is a 55 section through the line X X, Fig. 6, showing clearly the modification. Fig. 8 is another

modification. Fig. 9 is an enlarged transverse section on line 8 8, Fig. 5.

Similar letters of reference indicate similar or corresponding parts where they occur in 60 the several views.

My invention includes a blank of flexible wire A. This has its two ends B reduced or pointed in any well-known way, so as to form a double-ended pin. The said blank A has 65 formed on its center a bay or pocket C. This is formed by any suitable means, and when the pin is completed this bay forms the socket hereinafter mentioned. From this bay the wire is inclined slightly outwardly and then 70 downwardly. This forms the socket D. Each end of the wire is then bent upwardly, forming the sides, (marked E.) They are next turned toward one another and cross at the point marked F in the drawings. The said 75 ends are continued outwardly from each other to a convenient distance and form the legs G and G'. The distance these legs are extended determines the size or length of the pin. The said legs are then bent to form a 80 complete turn. The bending is continued until the wire has completed one turn and a half, thus forming at each end a spring H. The ends of the wire are then continued in- 85 wardly and form the free legs J and J'. The points B on the free legs J and J' meet each other when they are in position in socket D. My pin is now complete and ready for use. When it is desired to fasten the pin, the ends of the free legs J and J' are sprung into the 90 socket D and when in that position are sub- 95 stantially parallel with the legs G and G'. In a modification I may provide the said bay C with a lip K, as seen in Fig. 7. This is done in order that the ends of the free legs J and J' of the pin may be more securely locked in position within the socket previously mentioned.

In the modification shown in Fig. 8 the members E E are inclined toward each other 100 and meet at the point F, so that the form of the central part of the pin is approximately triangular instead of rectangular, as in Fig. 6. When used for suspending curtains, drapings, and the like, a suspending-hook S is 105 loosely connected around the said pin where the wire crosses itself, as seen at F in the drawings.

The cycle of operations for attaching my pin to curtains M, drapings, or the like is to 110 enter one point of the pin through a fold of the plait of the curtain and the opposite pin

through the opposite fold of the plait. The pins are entered from the back of the curtain, draping, or the like and are thus always out of sight. The two free legs of the pin are 5 with the fingers lifted into the socket. The plait can be adjusted by pulling it outwardly or inwardly upon the free legs of the pin. The hook S is then attached in the usual way to rings or poles from which the curtain M or 10 draping is to be suspended.

When using my improved pin upon wearing-apparel, in operation it is similar to that described, except that no suspending-hook is used.

15 Having thus described my invention, what I claim as new is—

1. A double safety-pin formed of a single piece of wire bent upon itself to form a central pocket portion and having its extremities 20 extended into opposite pin portions, the free ends or points of the pin portions being directed toward the pocket portion and adapted to be engaged therewith and be closed thereby, and the wire in each of the two pin 25 portions being bent one and a half times to form springs H, H, at that end of the pin portion farthest removed from the pin-point, all as shown and described.

2. The herein-described double safety-pin 30 formed of a piece of wire, bent centrally upon

itself to form a closed pocket as at F, by which it can be suspended, the legs G, G', being bent into oppositely-extending pin portions with their free ends pointing inwardly toward the pocket, and respectively adapted 35 to have their points engaged therewith and closed thereby, each leg being an elongation of the side of the pocket farthest removed from the pin-point, all substantially as described.

3. The combination of a double safety-pin formed of a single piece of wire bent upon itself to form a central pocket portion and having its extremities extended into opposite pin portions, the free ends or points of the 40 pin portions being directed toward the pocket portion and adapted to be engaged therewith and be closed thereby, each pin portion being an elongation of the side of the pocket portion 45 farthest removed from the point of the pin; 50 with a suspending device attached to the pocket portion where the wire crosses itself substantially as described.

In witness whereof I have hereunto set my hand to this specification in the presence of 55 two witnesses.

JOHN CUTHBERT TRAILL.
